UNITED STATES PATENT OFFICE.

HENRY CRIBBINS, OF SAULT DE STE. MARIE, MICHIGAN.

DESIGN FOR A BROOM-HOLDER.

SPECIFICATION forming part of Design No. 20,827, dated June 9, 1891.

Application filed June 13, 1890. Serial No. 355,393. Term of patent 3½ years.

To all whom it may concern:

Be it known that I, HENRY CRIBBINS, a citizen of the United States, residing at Sault de Ste. Marie, in the county of Chippewa and State 5 of Michigan, have invented a new and original Design for a Broom-Holder, of which the following is a specification.

My design consists, essentially, of two oppositely-disposed portions forming a flaring 10 mouth, each comprising a central wavy loop extending from said flaring mouth to a rectangular base, where the ends curve angularly outward and coil, and extending beyond these coils terminate in the base.

15 In the drawing illustrating my invention, A indicates a base-board; B B, two spring-wires bent into central wavy loops b b, hav-

ing their upper portions outwardly turned to form the flaring mouth B'. At the point where the loops b b touch the base-board A 20 20 the wires B B are turned angularly outward and coiled, as shown at b', whence they extend along the base-board, terminating at a.

I claim—

The design for a broom-holder herein described and shown.

In testimony that I claim the foregoing as my own I have hereto affixed my signature in presence of two witnesses.

HENRY CRIBBINS.

Witnesses:
